UNITED STATES PATENT OFFICE

CHARLES S. PRIZER, OF READING, PENNSYLVANIA.

DESIGN FOR A HEATING-STOVE.

SPECIFICATION forming part of Design No. 36,139, dated November 11, 1902.

Application filed October 15, 1902. Serial No. 127,427. Term of patent 7 years.

To all whom it may concern:

Be it known that I, CHARLES S. PRIZER, a citizen of the United States, residing in the city of Reading, county of Berks, State of Pennsylvania, have invented and produced a certain new, original, and ornamental Design for Heating-Stoves, of which the following is a specification.

My new and ornamental design for a heating-stove is shown in the accompanying perspective drawing, and the leading or material features thereof consist in the ornamented rounded corner-columns *a* of the casing, rising from the rectangular ornamented base *b*, with corresponding cross-bars *c* framing the ornamental lower and upper panels *d* and *e*, respectively, and the ornamental front door *f*, with the ornamental domed top *g* surmounting said columns and formed with concaved

reflectors *h*, overhanging said upper panels *e*. The columns and solid surfaces are ornamented with scrollwork in relief thereon, and the panels are of corresponding ornamental open scrollwork, as shown. Upon either side are projecting foot-rests *k*, hanging in front of said lower panel *d*, with the lower portions thereof flared outward and correspondingly ornamented with open scrollwork.

What I claim is—

The ornamental design for a heating-stove substantially as herein shown and described.

In testimony whereof I affix my signature in the presence of two witnesses.

CHARLES S. PRIZER.

Witnesses:

D. M. STEWART,
W. G. STEWART.
